UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

TRANSFERRING DEVICE.

Application filed May 16, 1927. Serial No. 191,745.

This invention relates to devices by which nails are conveyed from a receiving point, where they may be supplied by a distributor, to a delivering point, as over the die-block of a heel-attaching machine.

Devices of this character commonly include two receiving members mounted upon a carrier. One of these members, which is often called a loader-block, has openings in which 10 nails are temporarily retained by a shutter or gate, while the other is a block which occupies the space between the loader-block and die-block of the heeler and has openings which guide the nails into the latter upon their release by the shutter. It is necessary that the alignment between the loader-block and guide block openings shall be exact, to avoid interference with the passage of the nails through them, and, to establish and maintain this relation, a well-known practice is to support the loader-block upon the carrier-arm, and attach the guide-block to its under side by means of 20 screws and dowel-pins. Initially, this arrangement is successful as to the position of the guide-openings, but, in use, the jar caused by the striking of the loader-arm against the stops at the ends of its path of movement loosens the screws, and parallelism between the blocks is lost. Because of the resulting 25 misalignment of the openings, this may cause the nails to be caught and retained after they have been released. The displacement of the guide-block also interferes with the movement of the shutter. In addition to the difficulties which result from its use, the cost of 30 the screw-and-pin mounting of the guide-block is considerable.

Objects of this invention are to provide for secure, efficient support of the guiding member 40 or block. To this end, there are supported independently of each other, upon the arm or carrier of the illustrated nail-loading or transferring device, two receiving members, as the loader-block and the guide-block, through the aligned openings of which nails pass. This alignment is preferably maintained by means fixed to the carrier for engagement with each of the members. By this 45 direct separate support of each of the members upon their carrier, they may be made in-

dependent of such troublesome securing means as screws, and there is left between the members ample unrestricted space, in which a nail-retaining shutter may move. More specifically, an oscillatory loader arm is provided 55 with an opening, about which are two supporting surfaces of different diameters, one being shown herein as at the top of the arm, and the other upon a flange projecting into the opening at the bottom. Upon these respective surfaces, the loader-block and guide-block rest, and may be locked against rotation, with their openings in registration, by a key or other projection upon the arm. Not only are blocks so mounted free from liability to 60 displacement, and therefore the expense of maintenance is small, but the arrangement minimizes manufacturing costs, there being necessary little machine-work upon the parts. These nail-receiving blocks usually include in 65 their openings a multiple of all the nailing designs which are to be used. To limit the exposed portion of the members to a single set of these openings, I may mount separably upon the loader-block a plate containing only the 70 openings of the chosen set.

In the accompanying drawing, a particular embodiment of my invention is illustrated.

Fig. 1 being a sectional top plan view of the improved transferring device;

Fig. 2, a side elevation; and

Figs. 3 and 4, enlarged vertical, transverse sections on the lines III—III and IV—IV, respectively, of Fig. 1.

At 10 appears a vertical spindle, which may be fixed to the frame of a heel-attaching machine such as that illustrated in Letters Patent of the United States No. 1,157,688, Glidden, October 26, 1915, this frame not being shown. Arranged to oscillate about the spindle is a loader-arm 12, which may be moved by a handle 14 between nail-receiving and nail-delivering positions. The outer extremity of the arm is enlarged, to furnish a generally circular frame 16, which is preferably cast integral with said arm, it having a greater vertical thickness than the portion to which it is connected, as is shown in Fig. 3. This frame furnishes a carrier for a loader-block 18, in openings 20 in which the nails 100

are transferred, and for a block 22, through openings 24 in which the nails are guided for delivery. These openings in both blocks are identical in number and arrangement, usually being a multiple of all the nailing designs in accordance with which the machine supplied is to operate. The frame 16 surrounds an opening 26, which has about its top a horizontal annular finished surface 28, on which 10 rests a flange 30 at the top of the block 18. The lower portion of the opening 26 is of less diameter than the upper, there being an annular flange 32 providing a finished horizontal surface, parallel to the surface 28, supporting a flange 34 about the upper portion of the guide-block 22. To maintain the two blocks in the correct angular relation in the opening 26, with their sets of nail-receiving openings 20 and 24 in registration, each has 15 in its periphery a vertical slot, which receives a key 36. This key may have an outwardly extending projection 38, recessed into the top of the frame and secured in place thereon at 40. The lower face of the block 18 and the 20 upper face of the block 22 are parallel, and are spaced from each other at 42, and in this space, operating in close proximity to the under side of the block 18, is a nail-retaining shutter or gate 46. This shutter is pivoted 25 at 48 upon the arm 11, and is urged by a spring 50 out of the space 42, being temporarily retained beneath the openings 20 by a latch 44 to support the nails in them. Except 30 for the fact that this shutter is in no way limited as to its form by the supporting means for the block 22, it, with its controlling elements, may be arranged as is customary.

To present, at the top of the block 18, only that set of multiple openings which is to be employed at the time, there may be carried 40 upon the block a plate 52, which may be one of a group, having in it a single set of openings of the multiple in the blocks. Pins 54, 54, depending from the plate and entering 45 openings 56 in the block 18, produce the desired alinement of the openings in the plate with the corresponding set in the block. I prefer to furnish for each nailing design a plurality of plates of different thicknesses, a 50 second plate being partially indicated at 58. This permits such a plate to be chosen for the particular length of nail which is used that, with short nails n , the operator may still see the points above the plate and determine 55 whether the load is complete, while, with long nails N , a lateral support is afforded, so they may not become too far inclined from the direction of delivery.

It is to be observed that, in preparation 60 for the mounting of the loader and guide-blocks, it is only necessary to furnish upon them and the receiving frame the properly related supporting surfaces and key-receiving slots, and that assembling involves nothing more than dropping the blocks into their 65

places. Thus located, there is no possibility of displacement, and the renewal of worn or broken parts may be quickly accomplished.

Having described my invention, what I claim as new and desire to secure by Letters 70 Patent of the United States is:

1. A nail-transferring device comprising a carrier movable between nail-receiving and nail-delivering positions, and two members supported independently of each other upon 75 the carrier and each provided with a set of nail-receiving openings alined with those of the associated member.

2. A nail-transferring device comprising a carrier movable between nail-receiving and 80 nail-delivering positions, two members supported independently of each other upon the carrier with a continuous space between their adjacent surfaces and each provided with a set of nail-receiving openings alined with 85 those of the associated member, and a nail-retainer movable in the space between the members.

3. A nail-transferring device comprising a carrier movable between nail-receiving and 90 nail-delivering positions, two members supported independently of each other upon the carrier and each provided with a set of nail-receiving openings, and means fixed to the carrier for engagement with each of the members and arranged to maintain the nail-receiving openings in alinement.

4. A nail-loader comprising an oscillatory arm provided with an opening about which are supporting surfaces formed on the arm 100 and being of different diameters, a loader-block carried by one of said surfaces, and a guide-block carried by the other surface, the blocks containing sets of alined nail-receiving openings.

5. A nail-loader comprising an arm arranged to oscillate horizontally, said arm being provided with a vertical opening about the top of which is an annular supporting surface and an annular flange projecting into the opening at the bottom, a loader-block carried by the upper surface, and a guide-block carried by the flange.

6. A nail-loader comprising an oscillatory arm provided with an opening about which are nail-supporting surfaces of different diameters and a projection extending inwardly from both surfaces, a loader-block carried by one of said surfaces, and a guide-block carried by the other surface, the blocks containing 110 sets of alined nail-receiving openings and having recesses cooperating with the projection.

7. A nail-loader comprising an arm arranged to oscillate horizontally, said arm 125 being provided with a vertical opening about the top of which is an annular supporting surface and an annular flange projecting into the opening at the bottom, a loader-block carried by the upper surface, a guide-block car- 130

ried by the flange, both the loader-block and guide-block having peripheral recesses, and a key fixed to the arm over the supporting surface and flange and arranged to enter the recesses of blocks.

8. A nail-loader comprising an oscillatory arm provided with an opening about which are nail-supporting surfaces of different diameters, a loader-block carried by one of said

surfaces, a guide-block carried by the other surface the blocks containing a plurality of sets of aligned nail-receiving openings, and a plate separably mounted upon the loader-block and having a single set of openings registering with one of the sets in the blocks. 10

In testimony whereof I have signed my name to this specification.

THOMAS LUND.
